UNITED STATES PATENT OFFICE.

EUGENE LUDGER BARRIL, OF IRON RIVER, MICHIGAN.

AUTOMATIC TRAIN-STOP.

1,111,638.

Specification of Letters Patent.

Patented Sept. 22, 1914.

Application filed December 23, 1913. Serial No. 808,422.

To all whom it may concern:

Be it known that I, EUGENE LUDGER BARRIL, a citizen of the United States, residing at Iron River, in the county of Iron and State of Michigan, have invented certain new and useful Improvements in Automatic Train-Stops; and I do hereby declare the following to be a full, clear, and exact description of the invention, such as will enable others skilled in the art to which it appertains to make and use the same.

The primary object of this invention is to provide an automatic train stop which will first signal the engineer that a stop should be made and then operate upon the air-brake system to apply the air-brakes.

Another and more specific object of the invention is to provide an automatic train stop including a plurality of obstacles which may be operated by a semaphore or manually by a station master to engage a valve lever on the train and release air from the train line, whereby the brakes will be applied.

A further object of the invention is to provide in a device of this nature a means for placing torpedoes on the track in advance of the obstacle to warn the engineer that a stop should be made.

With these and other objects in view as will be become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a view showing in elevation my improved train stop as it appears in use, Fig. 2 is a top plan view, showing a portion of a track with the obstacle in operative position and the torpedoes in the path of the train wheels, Fig. 3 is a section taken on the plane of line 3—3 of Fig. 2, and Fig. 4 is a section taken on the plane of line 4—4 of Fig. 2.

Referring in detail to the drawings by numerals, 1 designates, as an entirety, a vehicle which may be the last coach of a train and which is equipped with a train line pipe 2 having a depending branch 3 which

is closed at its lower end by a valve 4 equipped with a lever or operating handle 5. The handle is normally held in such a position as to maintain the valve closed by a contractile spring 6 connected thereto at one end and at its other end to an arm 7 carried by the extension 3.

The obstacle, which I employ to engage the valve operating lever 5, consists of a rectangular frame 8, having a base bar 9, end bars 10 and a top bar 11, the latter being of a wavy construction. Trunnions 11' extend longitudinally from the ends of the base bar 9 through brackets 12 preferably supported on the cross ties 13. Arms 14 extending at right angles to the plane of the obstacle are formed on the ends of the trunnions 11' and when the obstacle is in operative position, project toward the track rails 15. A contractile spiral spring 16 is connected at one end to the top bar of the obstacle and at its other end to one of the cross ties 13 and tends to swing the obstacle away from the rail 15. A flexible connection 17 parallel the track rail 15, is guided by the pulleys 18, and is connected at one end to a lever 19. This lever is pivoted to any suitable support, such as indicated by the numeral 20, and may be locked in various positions by the catch 21 and quadrant 22. Staples, or other suitable fasteners 23, hold the flexible connection 17 in close proximity to the upper surfaces of the cross ties, and branch connections 24 connect the flexible member 17 to the arms 14. It will be apparent that when the lever 19 is swung in one direction, the spring 16 may act to pull the obstacle downwardly toward the cross ties and that when the lever 19 is swung in the other direction, the obstacle will be swung into a vertical plane against the action of the spring 16.

In order to signal the engineer before the brakes are set by passing over the obstacles 10, I employ a plurality of torpedoes 23. These torpedoes are carried on arms 24 which extend at right angles to a bar 25. This bar is provided with a pair of apertured pivot arms 26 which extend at right angles to the arms 24 and which are supported by a pivot rod 27 connected to brackets 28 positioned upon the cross ties 13. An arm 29 projects from each of the pivot arms 26 in the same direction and parallel to

the arms 24 and these arms 29 are connected to the flexible member 17 by branch connections 30, as clearly shown in Fig. 3. Expansive spiral springs 32 draw the bar 25 away from the rail 15 when the tension on the connection 17 is lessened, so that the torpedoes are carried from the path of the train wheels.

In operation, when it is desired to stop a train, a pull is exerted upon the connection 17 by swinging the lever 19 and the obstacles 10 and 11 are thrown into vertical planes and the torpedoes are arranged across the track rail 15. It will be understood that the connection 17 may be connected to and operated by a semaphore if desired. An approaching train will first explode the torpedoes to warn the engineer that a stop should be made and then the valve operating lever 5 will engage the wavy bar 10 of the first obstacle to cause an opening of the valve 4. This valve will be intermittently opened and closed by the combined action of the obstacle and the spring 6. It will be understood that as many obstacles as are necessary to cause a complete stoppage of the train may be employed.

From the foregoing description taken in connection with the accompanying drawings, it will be apparent that I have provided a very simple, practical and efficient train stop which will first warn the engineer that a stop should be made and, if this warning is disregarded, automatically cause the train to stop.

While I have shown and described the preferred embodiment of my invention, it will be understood that minor changes in construction, combination and arrangement of parts may be made without departing from the spirit and scope of the invention as claimed.

Having thus described my invention, I claim:

1. In an automatic train stop, an obstacle comprising a rectangular frame having a top bar of wavy construction, trunnions formed on the ends of the base bar of the frame, brackets through which said trunnions are journaled, an arm formed on each trunnion and extending at right angles to the plane of the obstacle, spring means for drawing the top bar of the frame away from the track and means for swinging the frame into a vertical position. 55

2. In an automatic train stop, the combination with an air-line controlling valve lever, of a track obstacle including a bar having its upper lever engaging face provided with alternate arcuate depressions and upstanding portions for intermittently operating said lever, depending arms formed upon said bar for pivotally supporting the bar adjacent a track and means for moving said bar into a lever engaging position. 60

3. In an automatic train stop, the combination with an air-line controlling valve lever, of a track obstacle including a bar having its upper lever engaging face provided with alternate arcuate depressions and upstanding portions for intermittently operating said lever, depending arms formed upon said bar for pivotally supporting the bar adjacent a track, means for moving said bar into a lever engaging position and means for automatically moving said bar from a lever engaging position after action of said first named means. 75

In testimony whereof I affix my signature in presence of two witnesses.

EUGENE LUDGER BARRIL
